UNITED STATES PATENT OFFICE

ALEXANDRE F. GODEFROY, OF MEXICO, MEXICO

SPORT JUMPING APPARATUS

Application filed January 6, 1930, Serial No. 418,877, and in Mexico September 3, 1929.

This invention relates to an apparatus that is intended to be used by a person suspended from a balloon for causing or assisting the balloon to rise when the balloon comes into close proximity to the ground or a body of water or any other surface or object over which the balloon passenger or user of the apparatus desires to travel.

The object of the invention is to provide an apparatus of the general type mentioned, that is easy to operate and which is of such design that it can be used successfully in connection with an inflated balloon for enabling a person to travel over ground or water, by a combined jumping and floating operation, without liability of being subjected to injury or discomfiture. The apparatus can be constructed in various ways, without departing from the spirit of my invention, but it will usually consist of a long handle, rod or staff adapted to be grasped at its upper end by a person sitting in a balloon basket or on a seat suspended from a small balloon inflated with sufficient gas to substantially balance the weight of the occupant or passenger, and a contact device at the lower end of the handle, which is of such a character or nature that when it is forced against the ground or against the surface of a body of water, or, in fact, against any object, by a downward thrust exerted on the handle, the resultant upward impulse produced by such action will assist the balloon to rise, and thus carry the passenger upwardly away from the surface or other object against which the contact device at the lower end of the handle was thrust. The apparatus is preferably equipped with a parachute arranged so that when the handle is moving downwardly said parachute will tend to resist such downward movement, and thus counteract the tendency of the balloon to drop or descend, and said apparatus is also preferably equipped with a buoyant element that forms a bearing surface at the lower end of the handle which will not sink or be submerged when the apparatus is thrust against a body of water to impart an upward impulse to the balloon and its occupant.

Figure 1 is a perspective view, illustrating

my improved sport jumping apparatus and the method of using same.

Figure 2 is an enlarged view of said apparatus, showing the parachute removed; and

Figure 3 illustrates the complete apparatus.

In the accompanying drawings which illustrate the preferred form of my invention, A designates a small balloon inflated with sufficient gas to substantially balance the weight of a person α sustained by a basket or seat B that is suspended from the balloon by a plurality of strands a of any suitable material. My invention consists of an apparatus that is adapted to be used by the passenger of the balloon to assist or cause the balloon to rise whenever the balloon drops to a level low enough to permit said apparatus to be thrust downwardly against a surface or object located directly beneath the passenger.

Said apparatus consists of a handle or staff 1 whose upper end is adapted to be grasped by one hand of a balloon passenger, as shown in Figure 1, and a contact device 75 at the lower end of said handle which provides a bearing surface for the handle of relatively great area. Said contact device preferably consists of a horizontally-disposed disk or wheel joined by upwardly converging bars or braces to the lower end of the handle 1.

In the form of my invention herein illustrated the bearing surface of the contact device is formed by a horizontally-disposed wheel 2, provided with wire spokes 3, and the rim of said wheel is joined by a plurality of upwardly inclined converging bars or braces 4 that are attached to the handle 1, as shown in Figure 2. If desired, said bearing surface may be provided with prongs 5 or any other suitable means, which will prevent or tend to prevent the contact device of the apparatus from slipping on the surface against which it is thrust.

In order that the apparatus may be used successfully as a thrust device to assist the balloon to rise when the balloon descends over a body of water, a buoyant element 6, preferably a rubber ball, is arranged at the lower end of the handle 1. In the apparatus

herein shown the ball 6 is confined in position or held in operative relationship with the handle 1 by the cage or skeleton-like structure formed by the disk or wheel 2 and converging bars 4 that join the same to the handle, said bars 4 being so proportioned that the ball 6 is capable of a certain degree of movement in its confining cage. By constructing the apparatus in this manner it can be used as successfully on water as on land for enabling a person suspended from a balloon to travel over a body of water by a combined jumping and floating action, due to the fact that the ball 6 has sufficient buoyancy when brought in contact with a body of water to resist downward movement of the handle 1, and thus cause the downward thrust which the user exerts on said handle to be applied in a direction to cause the balloon to rise.

As previously stated, the balloon A is inflated with sufficient gas to substantially balance the weight of the passenger, which balance can be obtained in numerous ways, as, for example, by sand ballast. After the weight of the passenger has been properly balanced, the slightest diminution in the weight of the load suspended from the balloon will cause the balloon to rise and float through the air a considerable distance before it again descends or approaches the earth. In fact, the release or discharge from the balloon basket of a few spoonfuls of sand or other ballast will cause the balloon to rise. In order to overcome the necessity of discharging ballast each time the balloon comes into close proximity with the ground, I have provided my apparatus with a parachute 7 which is so constructed and arranged that when the user or balloon passenger thrusts the handle 1 downwardly, said parachute tends to arrest or resist the downward movement of the handle, and thus produce an effect similar to that which can be obtained by discharging a small quantity of ballast from the balloon basket or support on which the passenger rests. In the form of my invention herein illustrated the parachute 7 is substantially cone-shaped, as shown in Figure 3, and the apex of same is attached to the handle 1 just above the point where the inclined bars or braces 4 are joined to the handle. While such a parachute is not absolutely essential to the successful operation of my apparatus, I prefer to equip the apparatus with a parachute or equivalent means that tends to resist the downward movement of the handle 1 before the contact device at the lower end of said handle comes into engagement with the surface against which the apparatus is thrust.

Having thus described my invention, what I claim as new and desire to secure by Letters Patent is:

1. A sport jumping apparatus adapted to

be used as a thrust device by the passenger of a balloon to assist the balloon to rise, composed of a staff or handle, and a buoyant device arranged at the lower end of said handle.

2. A sport jumping apparatus adapted to be used as a thrust device by the passenger of a balloon to assist the balloon to rise, composed of a staff or handle, a cage or skeleton-like structure at the lower end of said handle, and a buoyant device confined in said cage.

3. A sport jumping apparatus adapted to be used as a thrust device by the passenger of a balloon to assist the balloon to rise, composed of a staff or handle, a contact device having a bearing surface of relatively great area combined with the lower end of said handle, and a buoyant element combined with said contact device.

4. A sport jumping apparatus adapted to be used as a thrust device by the passenger of a balloon to assist the balloon to rise, composed of a staff or handle provided at its lower end with a contact device having a bearing surface of relatively great area, and a parachute combined with said handle to resist downward movement of same.

5. A sport jumping apparatus adapted to be used as a thrust device by the passenger of a balloon to assist the balloon to rise, composed of a staff or handle, a contact device at the lower end of said handle, a buoyant element combined with said contact device, and a parachute for resisting downward movement of the handle.

6. A sport jumping apparatus adapted to be used as a thrust device by the passenger of a balloon to assist the balloon to rise, composed of a staff or handle, a horizontally-disposed disk shaped element at the lower end of said handle provided with prongs, upwardly converging braces that join said element to the handle, and a buoyant element confined in the cage formed by said braces.

7. A sport jumping apparatus adapted to be used as a thrust device by the passenger of a balloon to assist the balloon to rise, composed of a staff or handle, a horizontally-disposed disk shaped element at the lower end of said handle provided with prongs, upwardly-converging braces that join said element to the handle, a buoyant element confined in the cage formed by said braces, and a cone-shaped parachute whose apex is attached to said handle at a point above the upper ends of said converging braces.
